UNITED STATES PATENT OFFICE.

CHARLES LEIGH, OF COLUMBUS, OHIO.

DESIGN FOR A COMBINED CLOCK CASE AND ELECTRIC LAMP.

Application filed September 17, 1926. Serial No. 19,103. Term of patent 3½ years.

To all whom it may concern:

Be it known that I, CHARLES LEIGH, a subject of the United Kingdom of Great Britain, and a resident of the United States, residing at Columbus, in the county of Franklin and State of Ohio, and whose post-office address is 1299 Roxbury Road, city of Columbus, State of Ohio, have invented a new, original, and ornamental Design for a Combined Clock Case and Elec-

tric Lamp, of which the following is a specification, reference being had to the accompanying drawing, forming part thereof.

The figure is a front elevational view of a combined clock case and electric lamp, showing my new design.

I claim:

The ornamental design for combined clock case and electric lamp, as shown.

CHARLES LEIGH.
